UNITED STATES PATENT OFFICE

JOHN F. MAURER, JR., OF WOODCLIFF, NEW JERSEY

BOX CONSTRUCTION

Application filed July 31, 1930. Serial No. 472,096.

This invention relates generally to the classes of boxes or crates and refers more particularly to milk bottle cases or the like.

In this class of containers, the walls are usually constructed of one or more panels of wood which, due to dampness, swell or expand and warp or otherwise distort the structure.

The present invention aims for one of its objects to provide a crate structure in which provision is made to overcome warping or distortion due to expansion or swelling.

The invention further comprehends a corner connecting and bracing device which, in addition to materially adding to the strength and length of life of the crate, effects a substantial economy in the assembly and production thereof.

More specifically the invention aims to provide a corner connecting and bracing device for box or crate structures consisting of a hollow member having angularly disposed wings in which the ends of the adjacent box walls are embracingly received together with interengaging means on the wings and embraced ends of said walls for securing the walls within the device.

With the above recited and other objects in view, reference is had to the following description and accompanying drawing, in which there is exhibited one example or embodiment of the invention while the claims define the actual scope of the same.

35 In the drawing:

Figure 1 is a fragmentary perspective view illustrating one corner of a box or crate constructed in accordance with the invention as viewed from the exterior.

40 Figure 2 is a similar view as viewed from the interior.

Figure 3 is a sectional plan view taken approximately on the line indicated at 3-3 in Figure 1.

45 Figure 4 is a similar view taken approxi-

mately on the line indicated at 4-4 in Figure 1.

Referring to the drawing by characters of reference, A and B designate respectively two of the walls of a crate or box which are in the nature of wooden panels and C designates generally the corner device for connecting and bracing the box or crate structure. The device C is of hollow construction and includes angularly disposed hollow wings 55 designated generally by the reference characters D and E in which the ends F and G of the adjacent panels A and B are embracingly received. In order to retain the panels or walls A and B in place within the corner 60 device C and in juxtaposition to each other, the embraced ends F and G are provided with vertical grooves H while the wings are slotted to provide inturned tongues I engaging with 65 the grooves.

In order to compensate for the expansion of the embraced ends F and G within the height of the panels A and B due to dampness, said ends are formed with inwardly extending horizontal slits J which are of a width to 70 freely receive therethrough the transverse horizontal rivets K in the wings D and E of the corner device C.

While the corner device C may be variously constructed, it preferably includes inner and outer angle plates 5 and 6, the former having angularly disposed leaves 7 and 8 and the latter having angularly disposed leaves 9 and 10. Each of the leaves 9 and 10 of the outer angle plate 6 are provided with inwardly directed upper and lower ends 11 and 12 formed respectively with a downwardly extending and an upwardly extending terminal 13 and 14. The terminals 13 and 14 are respectively joined by rivets 15 or equivalent securing means to the upper and lower ends of the leaves 7 and 8 of the inner angle plate 5 and, if desired, the lower end 16 of the inner angle plate 5 may extend below the lower end of the outer angle plate to pro- 80 85 90

vide a supporting foot for each corner of the box structure.

From the foregoing it will thus be seen that in practice the box may be economically assembled and produced in that the ends of the panels or walls have only to be introduced into the wings D and E of the corner devices C after which the tongues I are inturned to fit within the grooves H, thus completing the assembly of the side and end walls in an expeditious and inexpensive manner. Due to the embracing engagement of the corner devices with the ends of the box walls, a rigid and lasting connection is obtained while the slotted ends of the walls will allow for swelling or expansion without distortion or warping of the structure.

While there has been illustrated and described one form of the invention, it is to be clearly understood that no limitation is necessarily intended to the precise structural details but that variations and modifications which properly fall within the scope of the appended claims may be resorted to when desired.

I claim:

1. A box corner connecting and bracing device comprising a unitary member having angularly disposed hollow communicating wings each defining an open end of a size to snugly receive and embrace an end of the box wall and into each of which wings the ends of the adjacent box walls are embracingly received and interengaging means on each wing and embraced end of the box wall received thereby for securing the wall within the device, said embraced end having an inwardly extending horizontal slit to allow for expansion within its height and a horizontal rivet traversing the open end of the wing which rivet is freely received by the slit.

2. In a box or crate having side and end walls, a unitary corner piece having right angularly disposed hollow communicating wings each defining an open end of a size to snugly receive and embrace an end of the box wall and into each of which wings the adjacent ends of said walls are received, and a tongue and groove connection between said corner piece and said walls for permitting of the forcible insertion of the box walls in the open ends of the corner piece wings and for preventing relative displacement thereof, said wall ends being slotted inwardly to allow for vertical expansion within the height thereof and wing wall connecting means extending horizontally across the corner piece wings adjacent the open ends thereof and freely received by the slits at the ends of the walls.

3. A container including solid wooden side and end walls slotted inwardly from their ends to permit of expansion thereof and unitary corner elements having open ends for embracingly receiving and joining the adja-

cent slotted ends of said walls having means traverse the open ends of said elements and freely extending through the slits.

4. A corner construction for a box or crate including in combination with wooden side and end walls having vertically grooved faces at the ends thereof, hollow angulated unitary corner pieces within the opposite ends of which the adjacent ends of said walls are respectively embracingly received and spring means in the open ends of said corner pieces, engageable with said grooved faces for securing said walls in said corner pieces, and permitting of the assembly of the box walls with the corner pieces by forcible insertion of the same in the open ends of the corner pieces.

5. A corner construction for a box or crate including in combination with wooden side and end walls having vertically grooved faces at the ends thereof, hollow angulated unitary corner pieces within the opposite ends of which the adjacent ends of said walls are respectively embracingly received and spring means in the open ends of said corner pieces, engageable with said grooved faces for securing said walls in said corner pieces said means consisting of inwardly directed tongues formed integral with said corner pieces and engaging within the vertically grooved faces.

6. A corner piece for joining box or crate walls together including inner and outer angle plates having angularly disposed leaves, the leaves of the outer angle plate having inwardly directed upper and lower ends formed respectively with a downwardly extending and an upwardly extending terminal secured respectively to the upper and lower ends of the leaves of the inner plate to provide a unitary construction having hollow communicating angularly disposed wings, each having an open end for respectively receiving and into which open ends, the ends of adjacent walls of the box or crate are introduced for embracing engagement by said open wing ends, and rivets extending across the open ends of the wings and through the leaves of the inner and outer plates, the box walls having expansion slits extending inwardly from the ends thereof which are received by the open wing ends and which slits freely receive said rivets.

7. A box corner connecting and bracing device comprising a unitary member having angularly disposed hollow connecting wings each defining an open end of a size to snugly receive and embrace an end of the box wall and into each of which wings the ends of the adjacent box walls are embracingly received, resilient locking means on each wing and cooperative keeper means formed on the embraced ends of the box walls for automatically locking the walls within the device upon introduction of the wall ends into the wings.

8. A box corner connecting and bracing

device comprising a unitary member having angularly disposed hollow connecting wings each defining an open end of a size to snugly receive and embrace an end of the box wall and into each of which wings the ends of the 5 adjacent box walls are embracingly received and interengaging means on each wing and the end of the box wall which is received thereby for automatically locking the wall within the wing, said means consisting of a 10 grooved side of the box wall end and an instruck resilient tongue on the wing adapted to snap into the grooved side upon introduction of the box wall end into the wing.
